UNITED STATES PATENT OFFICE.

CHARLES A. PITKIN, SR., OF SAN JOSÉ, CALIFORNIA.

FRUIT-DRIER.

SPECIFICATION forming part of Letters Patent No. 374,698, dated December 13, 1887.

Application filed June 4, 1887. Serial No. 240,335. (No model.)

To all whom it may concern:

Be it known that I, CHARLES A. PITKIN, Sr., of San José, county of Santa Clara, State of California, have invented an Improvement 5 in Fruit-Driers; and I hereby declare the following to be a full, clear, and exact description of the same.

My invention relates to certain improvements in fruit-driers, and is an improvement 10 upon a former application filed by me, Serial No. 236,361, filed April 27, 1887.

My invention consists in the constructions and combinations of devices which I shall hereinafter fully describe and claim.

15 Referring to the accompanying drawings for a more complete explanation of my device, Figure 1 is a vertical transverse section of the apparatus, taken through the lines X X, Fig. 2. Fig. 2 is a longitudinal vertical section taken 20 through the apparatus. Fig. 3 is a horizontal section taken on line Y Y, Fig. 1.

A is the shell or case of the drier, having mounted within it the wheel B, formed with radial arms, and having the tray-carrying 25 boxes suspended from rods upon the ends of these arms, so as to maintain a horizontal position while the wheel is rotated by suitable machinery.

In the lower part of the apparatus is a furnace, D, its products of combustion passing 30 out through the pipes E, these pipes being carried backward and forward a sufficient number of times so that the air in the lower portion of the drier will be fully exposed to their heating influence, after which they are led into 35 a pipe, F, connecting with the vertical flue or chimney G.

H is a deflecting plate or diaphragm, by 40 which the heated air is directed upward at what I will call the "rear portion" of the chamber, so as to come in contact with the fruit supported in the trays upon the revolving wheel. As this air becomes loaded with moisture, it is necessary to provide some means for 45 conveniently removing it without losing the drier portion, and in order to do this I take advantage of its tendency to gravitate toward the lower part of the chamber. Upon each side of the furnace are chambers or receptacles 50 H', as shown in Fig. 1, and extending across above these is a movable plate or damper, I,

which extends the full width of the apparatus, as shown in Fig. 3, and is provided with handles J, by which it may be drawn out or closed at will. This damper being open, the moist 55 air, after circulating through the upper part of the chamber and becoming loaded with moisture from the fruit, as well as being somewhat cooled by the contact, will settle toward the lower part of the chamber above the deflecting-plate H, and the damper or plate I being open it will find its way into the chamber H' at the lower part of the apparatus. These chambers being full of the moist air, the damper or diaphragm I is closed, so as to 60 temporarily cut them off from the upper portion of the drying-chamber, when the moist air may be removed either by opening doors connected with the chamber or by means of a pipe, K, leading from the chamber into the 65 pipe F, which conveys the waste heat from the pipe E to the chimney G.

By extending the pipe K some distance within the pipe F the temperature of air therein will be raised and a considerable draft 70 caused by reason of the expansion, and will consequently act to remove the heavy moist air from the chamber H'.

L is a vertical flue or chamber which extends the full height of the apparatus at the 75 side, and has a door, M, opening outwardly from it. In my present invention I place the valve N in the upper part of this chamber, and when the valve is open any moist air which may pass over the top of the vertical 80 partition which separates the chamber L from the remainder of the drier will enter the chamber and settle to the bottom. This receives a considerable portion of the heavy moist air which may have a tendency in that direction, 85 and when the chamber L has become filled with it the valve N at the top is closed. The door M may then be opened, so as to discharge this moist air, without any danger of an upward draft or cold air entering the drying-chamber, as the valve N temporarily cuts off 90 this communication. After the chamber L has been emptied of the moist air, the door M may again be closed and the valve or damper N opened to admit another charge. In this way 95 I provide a convenient means for clearing the apparatus of moist heavy air from time to time 100

without cooling it off or losing any great amount of hot air, which is still valuable for drying purposes.

Having thus described my invention, what I claim as new, and desire to secure by Letters Patent, is—

1. In a fruit-drying chamber, the heater or stove, the heating-pipes, and the horizontal deflecting-plate, together with the rotating wheel carrying the fruit-drying trays, in combination with the vertical side chamber or passage communicating at the top with the drying-chamber, a door, M, in the side of said chamber or passage and opening outwardly, and a valve or damper, N, in the top of the chamber or passage, by which the upper end of the chamber may be closed and cut off from the drier temporarily, substantially as described.
2. In a fruit-drier, the heater deflecting-plate and the tray-carrying wheel contained within the exterior case, in combination with the chambers in the lower part at each side of the furnace for the reception of moist heavy

air, and a valve or damper, I, extending across the top of said chambers, whereby the chambers may be cut off from the upper portion of the drier while being discharged of the moist air, substantially as described.

3. In a fruit-drier, the outer case having the heater or furnace, the heating-pipes extending therefrom and opening into a pipe connecting them with the chimney, a deflecting-plate, and a tray-carrying rotating wheel, in combination with the moisture-receiving chambers at the lower part of the apparatus, with the valve or damper by which they are cut off from the remainder of the drier, and the pipes leading from these chambers into the pipe F, which conveys the waste heat to the chimney, whereby a draft is produced from the moisture-chambers, substantially as herein described.

In witness whereof I have hereunto set my hand.

CHARLES A. PITKIN, SR.
